UNITED STATES PATENT OFFICE.

THEODORE CLOUGH, OF NEW YORK, N. Y.

IMPROVEMENT IN GAS-BURNERS.

Specification forming part of Letters Patent No. 120,715, dated November 7, 1871.

To all whom it may concern:

Be it known that I, THEODORE CLOUGH, of the city, county, and State of New York, have invented a new and useful Improvement in Gas-Burners; and I do hereby declare that the following is a full, clear, and exact description of the same, reference being had to the accompanying drawing and to the letters of reference thereon.

The invention relates more particularly to burners for burning illuminating gas made by saturating air with vapors of gasoline, commonly called air-gas; and is an improvement upon the burner for which Letters Patent No. 104,271 were issued to me June 14, 1870; and whereby the common bat-wing or fish-tail burner may be used for such gas notwithstanding its variable density as it comes from the generating apparatus, said adaptability being effected by perforating the base of the burner-tube with a hole or holes for gas to escape at the base of the burner and surrounding the burner with a tube, open at the top but closed at the bottom, and united to the burner below said hole or holes in the burner-tube. To regulate the escape of the gas from the hole or holes at the base of the burner I have heretofore used a sliding tubular valve or cut-off introduced into the base of the burner and extending upward within it, the position of the tubular valve being regulated by an annular screw, to which the burner occupies a concentric relation. This invention consists in an improvement upon such construction by a combination of a side regulating-screw (which device is not claimed of itself) with the burner perforated at its base and the surrounding tube, whereby I am enabled to greatly simplify and cheapen the production of my improved burner as a whole, and to furnish a regulated supply of gas outside of the burner proper, but directed to the tip of the burner by the surrounding tube to give steadiness and increased illuminating power to the flame of the burner.

The drawing represents a bat-wing burner

with my improvement applied to it. Figure 1 is an elevation of said burner and improvement. Fig. 2 is a vertical section of the same in a plane at right angles to Fig. 1, and Fig. 3 a transverse section at the line *x x* in Fig. 2.

Similar letters of reference indicate corresponding parts.

a represents the burner-tip; *b*, the burner-tube; and *c*, a side hole or perforation at the base of the burner-tube. *d* is the surrounding tube, screwed to the base of the burner-tube. *e* represents the side regulating-screw, arranged to pass or screw through the surrounding-tube *d* and burner-tube opposite the side hole or perforation *c*, through which the gas passes to surrounding-tube when said hole is not closed by the screw that serves, accordingly as it is screwed in or out—that is, toward or from the hole *c*—to regulate the supply of gas to the outside of the burner-tube, and into which hole *c* or female thread therein the screw *e* may also fit. An annular groove, *f*, may be made in the outside of the burner-tube, to facilitate the distribution of the supply of gas around said tube as it issues from the orifice *c*. The burner, as a whole, need not by this construction be disturbed from its place of attachment to the gas-pipe to regulate the supply of gas to the outside of the burner-tube, and the number or extent of annular screw-threads is diminished as compared with the construction of the burner previously patented by me, as hereinbefore referred to.

What is here claimed, and desired to be secured by Letters Patent, is—

The side regulating-screw, in combination with the burner-tube perforated at its base and the surrounding tube for regulating the supply of external gas to the burner, substantially as specified.

THEODORE CLOUGH.
